UNITED STATES PATENT OFFICE

2,566,506

IRRIGATION WELL COOLING SYSTEM

Gustav Thieszen, Henderson, Nebr.

Application April 25, 1949, Serial No. 89,503

3 Claims. (Cl. 123—41.31)

1

This invention relates to an improved cooling means for stationary engines.

An object of this invention is to provide an improved cooling means for stationary engines connected to irrigation well pumps wherein the water which is pumped by the engine will provide a cooling medium for the water in the engine cooling system.

Another object of this invention is to provide an improved cooling jacket which is interposed in the cooling system of the engine and is disposed about the discharge pipe of the pump which is driven by the engine, so that the cool water discharged from the pump will cool the jacket and maintain the water in the latter cool.

With the above and other objects in view, my invention consists in the arrangement, combination and details of construction disclosed in the drawings and specification, and then more particularly pointed out in the appended claims.

In the drawing,

Figure 1 is a detail side elevation of an irrigation pump and engine connected therewith having a cooling system constructed according to an embodiment of this invention, connected with the engine and the pump,

Figure 2 is a detail end elevation of the pump and engine,

Figure 3 is a sectional view taken on the line 3—3 of Figure 2,

Figure 4 is a sectional view taken on the line 4—4 of Figure 3,

Figure 5 is a fragmentary sectional view taken on the line 5—5 of Figure 3,

Figure 6 is a fragmentary sectional view taken on the line 6—6 of Figure 5.

Referring to the drawing, the numeral 10 designates generally a pump which is connected with an irrigation well and which is operated by means of an engine 11. The engine 11 is connected with the pump 10 by means of a shaft 12, and the engine 11 includes a cooling jacket 13 having an outlet 14 and an inlet 15. The water which is discharged from the pump 10 passes through a discharge pipe or water main 16 which is threaded into a collar 17 and secured by fastening means 18 to the discharge side of the pump 10. A water reservoir 19 is disposed adjacent the pump 10 being connected with the discharge nipple 14 of the engine jacket 13 by means of a tubular member 20. The reservoir 19 is supported adjacent the discharge side of the pump 10 by means of a pair of vertically disposed angle members 21 which are

2

secured to the collar 17 by a pair of the fastening members 18. The water discharged into the reservoir 19 passes downwardly through an outlet 22 and enters a cooling jacket generally designated as 23.

The jacket 23 is interposed in the discharge pipe 16 and is formed of an inner wall 24 forming a bore alignable with the discharge opening of the pump 10 and may be formed of corrugated construction to provide an increased cooling surface, and the jacket 23 also includes an outer cylindrical wall 25. A pair of end walls 26 and 27 are secured to the walls 24 and 25 and the outer wall 25 is provided with an intake nipple 28 connected with the outlet 22 of the reservoir 19, by means of flexible hose 29. The outer wall 25 also has a lower outlet nipple 30 with which a flexible hose 31 is connected, and the hose 31 is connected with an elongated pipe 32 which is connected to a relatively short flexible hose 33. The hose 33 is connected to the intake nipple 15 of the engine jacket 13.

In the use and operation of this device, the jacket 23 is interposed between the ends of pipe 16, being welded or otherwise secured thereto so that the water will flow through the jacket 23 within the confines of the inner wall 24, and the reservoir 19 is supported by the supporting bars 21 from the pump 10. The hot water from the engine will pass through the outlet connection 20 into the top of the reservoir 19, and the water will then pass downwardly through the hose 29 into the cooling jacket 23. The cool water passing through the inner wall 24 of the jacket 23 will cool the jacket and thereby cool the water entering the jacket 23 which is then returned to the engine 11 through the return connections 31, 32 and 33. The cooling means hereinbefore described will take the place of the radiator which is at present associated with the engine 11 and will eliminate the fan and other cooling means.

I do not mean to confine myself to the exact details of construction herein disclosed, but claim all variations falling within the purview of the appended claims.

What I claim is:

1. In an internal combustion engine having a cooling jacket, a pump operated by said engine and connected to a water well for withdrawal of water therefrom, a discharge pipe extending from said pump, a reservoir connected with the outlet side of said cooling jacket, a cooling member interposed in said discharge pipe having a surrounding water chamber disposed radially of said discharge pipe, a connection between said cool-

ing member and said reservoir, and a connection between said cooling member and the intake side of said jacket.

2. In an internal combustion engine having a cooling jacket, a pump operated by said engine and connected to a supply of water, a water main extending from said pump for conducting a flow of water therefrom, a reservoir connected with the outlet side of said cooling jacket, a tubular cooling member having a circular passage encircling said water main, a connection between said cooling member and said reservoir, and a connection between said cooling member and the intake side of said jacket.

3. In an internal combustion engine having a cooling jacket, a pump disposed above a water well connected to and operated by said engine for pumping water from said well, a discharge means opening from said pump, a reservoir connected with the outlet side of said cooling jacket, means supporting said reservoir from said pump, a cooling member connected to said discharge means,

said cooling means being formed as an extension of said discharge means with an inner wall engageable by the pumped water, a surrounding wall spaced from said inner wall having spaced end walls extending inwardly therefrom to form a chamber disposed radially of said discharge means, a connection between said cooling member and said reservoir, and a connection between said cooling member and the intake side of said jacket.
